UNITED STATES PATENT OFFICE.

EDWARD W. NEWELL, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

DRAFT-GEAR ATTACHMENT.

1,232,594.

Specification of Letters Patent. Patented July 10, 1917.

Application filed January 23, 1915. Serial No. 3,888.

To all whom it may concern:

Be it known that I, EDWARD W. NEWELL, a citizen of the United States, residing at Pittsburgh, in the county of Allegheny and State of Pennsylvania, have invented new and useful Improvements in Draft-Gear Attachments, of which the following is a specification.

This invention relates to draft gear attachments, and more particularly to that type employing keys.

With the above type of draft gear attachment there is usually present a certain amount of lost motion or play between the moving parts dependent upon the nicety of alignment and the accuracy with which the keys are fitted in the bearing slots and upon the extent that wear has taken place.

This lost motion subjects the gear to impact or hammer-like blows when buffing or draft stresses are applied to the draw-bar and is therefore undesirable and moreover, the capacity of the draft gear is reduced since the full movement of the draw-bar may not be transmitted to the draft gear.

The principal object of my invention is to provide means for taking up and maintaining the draft gear rigging free from lost motion.

Broadly stated, I accomplish the above object by providing a wedge device for placing the draft gear spring under initial compression and so disposed that the initial compression of the spring reacts on the draft rigging to take up and maintain the same free from lost motion.

In the accompanying drawings; Figure 1 is a horizontal section of a draft gear embodying my improvement; Fig. 2 a vertical section thereof; Fig. 3 a view similar to Fig. 1, showing how the parts are assembled; Fig. 4 a horizontal section of a draft gear with a slightly modified form of my invention applied thereto; Fig. 5 a vertical section thereof; Fig. 6 a transverse section on the line *a—a* of Fig. 5; and Figs. 7 and 8 central sectional views of a stationary key of the type shown in Fig. 1, but illustrating different forms of wedges for placing the draft springs under initial compression.

According to the construction shown in Figs. 1, 2, and 3 of the drawings, the draft gear attachment is of the key type having a front key 1 passing through a slot in the draw-bar 2 and movable therewith, the cen-

ter sills 3 having elongated slots 4 to provide for the movement of the key.

Rearward of the movable key 1 is a stationary key 5 which fits slots in the center sills, the keys 1 and 5 extending through the respective elongated slots 6 and 7 in the yoke 8 within which is mounted the draft gear 9.

The rear end of the draw-bar 2 bears against a block 10 having an elongated slot 11 for the stationary key 5 and the draft spring 12 of the draft gear 9 engages the rear face of said block.

According to the form of my invention shown in Figs. 1, 2, and 3 of the drawings, the stationary key 5 is made up of a central wedge 13 and coöoperating side pieces 14, so that by driving the central wedge therebetween, the side pieces are forced apart.

In assembling the draft gear parts in the car, the draft gear 9 and the yoke 8 are placed in position with the block 10 mounted between the rear end of the draw-bar 2 and the forward end of the draft spring 12. The side pieces 14 are then inserted through the slots in the center sills 3 and the slot 11 in the block 10 and the central wedge 13 is placed in driving position between the side pieces 14, so that the parts are positioned as shown in Fig. 3. The central wedge 13 is now driven home, causing the side pieces to separate, so as to fill the slots in the center sills, and this movement also causes the rearward movement of the block 10, compressing the draft spring 12 so as to put the same under initial compression, since the draft gear is held against movement by the yoke 8 which can not move rearwardly on account of the engagement with the key 5 at the forward ends of the slots 7.

When the central wedge 13 has been driven home, the same may be locked against withdrawal by a pin 15 or other locking device.

The rearward movement of the block 10 permits the rearward movement of the draw-bar 2, so that the slot therein is brought into alignment with the slots 6 in the yoke. The front key 1 may now be inserted in position, so that normally the parts will be in the position shown in Fig. 1.

The pressure of spring 12 therefore acts constantly on the rear face of the block 10 and reacts through the yoke 8, so that the forward ends of the slots 7 always bear tightly against the stationary key 5, thus

eliminating lost motion or play, even after the parts become worn. The key 5 being wedged tightly in the slots through the center sills, prevents any lost motion of this key.

Other forms of wedges may be employed, such as those shown in Figs. 7 and 8 of the drawings. In the Fig. 7 construction, the central wedge 13' is provided with separate pairs of oppositely inclined wedge surfaces 16 and 17 arranged at the ends of the wedge, a clearance space being provided intermediate the wedge surfaces. By this arrangement, the angle of the wedge faces may be made more obtuse, so as to reduce the movement necessary to drive the wedge home.

In the Fig. 8 construction, two central wedges 13'' are employed, which are adapted to be driven between the side pieces 14'' from opposite sides. This construction permits the use of wedges half the length of the wedges employed in the Figs. 1 and 7 constructions, which may in some instances be desirable, where clearance space is limited and will not permit the insertion of a long wedge.

In Figs. 4, 5, and 6 of the drawings, the wedge device for placing the draft spring under initial compression comprises a member 18 having a wedge shaped section and provided with ears 19 extending rearwardly and having elongated slots 20 for the stationary key 5''. The member 18 has its forward face bearing against a follower 21, the draw-bar 2 engaging the front face of the follower.

Said follower has lateral projections 22 adapted to engage in elongated slots 23 of the yoke 3'.

40 Mounted between the ears 19 of the member 18 is a block 10' having a forward inclined face adapted to coöperate with the inclined wedge face of the member 18, the draft spring 12 bearing against the rear face thereof.

In the present instance, the parts are assembled by placing the draft gear 9 in position within the yoke 8' as well as the follower plate 21, and the block 10' with its rear face engaging the spring 12. The wedge member 18 is now driven home from

below, which operates to compress the spring 12 and bring the elongated slot 11' of the block 10' into alinement with the slots 7 of the yoke. The parts above described may now be mounted on the car with the rear slots in alinement with the slots in the center sills for the stationary key, which is then inserted, as also the front movable key 1.

In this instance, the spring 12 presses the block 10' and the member 18 against the follower 21 and reacts through the yoke 8' to maintain the front ends of the slots 23 in the yoke tightly against the follower, so as to prevent lost motion.

Having now described my invention, what I claim as new and desire to secure by Letters Patent, is:—

1. The combination with a draft gear 70 having a draft spring and a yoke inclosing the draft gear, of a wedge device for placing the spring under initial compression and acting as an abutment for holding the yoke against the reaction of the spring, thereby 75 maintaining the yoke constantly under tension.

2. The combination with a draft gear having a draft spring and a yoke inclosing the draft gear, of a key extending through slots 80 in the yoke and including a wedge for placing the spring under initial compression.

3. The combination with a draft gear having a draft spring, of a stationary key forming a stop under buffing and draft stresses 85 and a wedge forming part of the key for placing the spring under initial compression.

4. The combination with a draft gear having a draft spring and a yoke inclosing the draft gear and having elongated slots, of a stationary key mounted in the slots of the yoke and acting as a stop under draft movements in both directions, said key including a wedge adapted to place the draft spring under initial compression.

In testimony whereof I have hereunto set my hand.

EDWARD W. NEWELL.
